WARNING SIGNAL LIGHT UNIT

Smith H. Brown, Downey, Calif., assignor, by mesne assignments, to Curtiss-Wright Corporation, a corporation of Delaware

Application May 7, 1958, Serial No. 50,780

Term of patent 14 years

(Cl. D72—1)

FIG. 1

FIG. 2

FIG. 3

FIG. 4

Figure 1 is a perspective view of a warning signal light unit, showing my new design;

Figure 2 is a side elevational view thereof;

Figure 3 is a top plan view thereof; and,

Figure 4 is a bottom plan view thereof.

I claim:

The ornamental design for a warning signal light unit, substantially as shown.
